TAMPING MACHINE

Ernst F. Muller, Columbus, Ohio, assignor to The Jeffrey Manufacturing Company, a corporation of Ohio

Application September 20, 1933, Serial No. 690,181

3 Claims. (Cl. 105—27)

This invention relates to apparatus for injecting tamping material into a drill hole in a mine after a blasting charge has been placed in such hole, and effecting the tamping of such material in the drill hole.

One of the objects of the invention is the provision of improved and efficient apparatus adapted to be mounted on a truck traveling on a mine track and operable under the control of the operator by air pressure for introducing and tamping granular material such as stone dust or sand into a drill hole after a blasting charge has been placed therein.

Another object of the invention is the provision of mechanism for controlling the air supply for the maintenance of proper pressure thereof at all times.

A further object of the invention is the provision of a pressure system controlled clutch for controlling a driving connection between a motor and a driving wheel of a mining machine, which pressure system includes a pump driven by the motor.

Other objects of the invention will appear hereinafter, the novel features and combinations being set forth in the appended claims.

In the accompanying drawings:

Fig. 1 is a plan view of truck-mounted apparatus embodying the present improvements;

Fig. 2 is an elevation of the truck-mounted apparatus shown in Fig. 1;

Fig. 2a is a detail view of the control valve between the compressor and the storage tank;

Fig. 3 is a sectional elevation taken on the line 3—3 of Fig. 2, looking in the direction of the arrows;

Fig. 4 is an enlarged elevational view of the controlling mechanism for the compressor shown mounted on the truck in Figs 1 and 2; and

Fig. 5 is an enlarged sectional elevation of the controlling mechanism for the compressor shown mounted on the truck in Figs. 1 and 2; and

Referring more particularly to the drawings and especially to Figs. 1 and 2, a truck frame 6 is mounted on wheels 7, 7, adapted to travel on a mine track 8. By means of a lever 9 pivoted at 10 and connected through the link 11 to the brake shoe 12, the truck frame may be retarded in its movement along the mine track or held on the latter in a stationary position. The lever 9 may be held in brake applying position by the usual pawl and ratchet mechanism comprising the ratchet 11'.

An electric motor 13 mounted on the truck frame 6 is connected by means of the spur gears

14, 15 to an air compressor 16 which comprises an operating shaft 17. This shaft extends loosely through a sheave 18 which may be connected to the shaft by means of a clutch 19 operable by means of a lever 20 pivoted at 21 and held in adjusted position by a latch 20' on an auxiliary lever 22 pivoted at 23.

When power from the motor 13 is applied to the sheave 18, the endless rope 24 acts as a belt to transmit rotary movement to the sheave 25 on the cable reel 26. An electrically insulated cable 27 is connected to the electric motor 13, wound on the reel 26 and then extended through the winding guiding mechanism 28 to a distant source of electric supply. A driving sprocket 29 is mounted on the axis of the shaft 17 and is connected by the sprocket chain 30 to a driving sprocket 31 on the forward axle 32 of the wheel-mounted truck. By means of a lever 33 pivoted at 34 and connected at 35 to a clutch 36, the latter may be applied to effect the transmission of power from the electric motor 13 to the sprocket chain 30 to effect propulsion of the entire machine along the mine track for transportation in the mine. The lever 33 may be held in either clutch releasing or clutch applying position by means of the latch 22', 33'.

The air compressor 16 is connected by a pipe 37 to a compressed air storage tank 38 which is mounted on the forward end of the truck 6 and secured thereto by the straps 39, 39, the ends of which are secured to the upper frame 40 and the lower standards 41. The air pressure in the tank 38 may be indicated by the pressure gauge 42. The flow of compressed air from the compressor 16 through the pipe 37 into the compressed air tank 38 may be controlled by means of the valve 43. When the lever 44 is in the horizontal position shown in Fig. 2, communication may be established between the compressor 16 and the tank 38 with the exhaust port 45 closed. When the lever 44 is moved to a vertical position extending below the pipe 37, the latter may be closed and the compressor 16 connected through the exhaust port 45 to the atmosphere. When the compressor 16 is connected to the atmosphere through the exhaust port 45, the electric motor 13 will be free to rotate either the sheave 18 when the clutch 19 is applied or the sprocket 29 when the clutch 36 is applied; or both the sheave 18 and the sprocket 29 may be operated at the same time. If the air pressure in the storage tank is below normal, the latter can, if desired, be filled up to 55

normal pressure while traveling from one place to another, thus saving time.

After the truck with the apparatus mounted thereon as shown in Figs. 1 and 2 has been transported to a position near a coal face, the brake 12 may be applied to hold the truck stationary on the mine track and the lever 44 moved to its horizontal position shown in Fig. 2. The electric motor 13 may then be operated while the clutches 19 and 36 are released. In order to secure automatic control of the pressure in the tank 38, the mechanism shown in Fig. 5 may be provided. The spur gear 15 is mounted in the casing 46 to rotate loosely around the shaft 17. A cylindrical clutch element 47 extends from one side of the spur gear 15 and is provided on its inner cylindrical wall with a plurality of circumferentially spaced webs 48 which fit into slots of the clutch disks 49. The latter alternate with 20 an additional set of clutch disks 50, the inner edges of which are provided with slots fitting the circumferentially spaced webs 51 on the clutch element 52 which is keyed to the shaft 17 as indicated at 53.

25 Between the ring 54, which is secured to the spur gear 15 between the clutch elements 47 and 52, and the circular thrust cap 55, the clutch disks 48 and 50 are arranged as shown in Fig. 5. The central portion of the circular thrust cap 55 is cylindrical and cup-shaped to fit over the left-hand end of the shaft 17. The outer cylindrical portion 56 of the cap 55 forms a cylindrical bearing for the ring 58 which is secured to the clutch element 47 to effect an enclosure for the clutch disks.

A thrust pin 59 is secured to the operating arm 60 by means of the nut 61 in position to engage the outer central portion of the cap 57. An opening may be provided at 62 for the introduction of a lubricant to the shaft 17, thereby lubricating the relative rotation between the thrust cap 55 and the shaft 17. The opening 62 also permits free movement of the clutch element 57 relatively to the shaft 17.

45 The upper end of the operating lever 60 is pivoted at 63 to the bracket 64 which is secured to the casing cover 46. The lower end of the operating lever 60 is provided with a fork 65, the lower ends of which are pivoted at 66 to a pair of horizontal links 67, 67, the right-hand ends of which are connected by a cross rod 68 slideable in longitudinal slots 69 in the rear portions of the walls of the cylinder 70.

In the cylinder 70 is an elongated piston 71 which is adapted to slide along the cylinder 70 when air under sufficient pressure enters the chamber 72. The right end of the piston 71 as shown in Fig. 5 engages the transverse rod 68 which extends transversely of the chamber 73. 50 Inasmuch as the chamber 73 communicates with the atmosphere through the slots 69, the piston 71 is free to slide along this chamber so far as air pressure therein is concerned.

Movement of the piston 71 toward the left along the chamber 72 is limited by the center pin 74 striking against the end wall 75 of the chamber 72. When the pin 74 engages the wall 75, the left-hand end of the piston 71 will be adjacent the port 76 but will not close the same.

In the recess 77 in the left-hand end of the shaft 17 as viewed in Fig. 5 is a spring 78 which engages a cylindrical plug 79 bearing against the bottom of the thrust cap 57. When the air pressure in the chamber 72 is relieved so as to free

the operating lever 60, the spring 78 will release the friction clutch 49, 50.

Mechanism is provided for operating the friction clutch automatically if sufficient pressure is available from the compressed air storage tank 38. The latter is connected by means of the pipe 97 to the chamber 72 of the valve structure shown in Fig. 5. When the valve 95 is opened the compressed air passes through the port 76 into the chamber 72 and moves the piston 71 toward the right to cause the latter to exert pressure against the pin 68 to actuate the lever 60 in an anti-clockwise direction. The thrust pin 59 will then exert a pressure against the central part of the thrust cap 57, which pressure is transmitted against the friction disks 49 and 50. Since the friction disks 49 are revolving with the gear 15, the frictional resistance between the disks 49 and 50 will cause the compressor shaft 17 to be rotated.

20 After the friction clutch shown in Fig. 5 has been applied to connect the motor 13 to the air compressor 16, connection will also be established between the motor 13 and the shaft 17 in Figs. 1 and 2. Therefore, whenever desired, the reel 26 may be rotated by operating the lever 20 to apply the clutch 19. Also when desired the shaft 17 may be connected to the truck propelling sprocket chain 30 by actuating the lever 33 to apply the clutch 36. The clutches 19 and 36 may be applied individually or simultaneously and held in applied or released positions by the latches 20' and 33'.

25 During forward movement of the machine, clutch 36 is applied, but clutch 19 is released to permit free rotation of the reel 26 to pay out the cable 27 while at the same time the truck propelling mechanism is being operated. During rearward travel of the machine both clutches are applied to effect winding up of the cable on the reel during rearward movement of the machine along the mine track. Slipping of the belt 24 on the drive sheave 18 may be relied on to compensate for the increasing diameter of the convolutions of cable on the reel.

30 Furthermore, as above explained, if the air pressure in the storage tank 38 falls below normal as indicated by the pressure gauge 42, the valve 64 may be opened and the air compressor permitted to operate to restore the air pressure to normal in the storage tank 38 during transportation of the machine.

The automatic control of air pressure in the compressed air tank 38 may be understood by referring to Fig. 5 in connection with Fig. 1. 35 When the valve 95 is opened and the pressure in the storage tank 38 is below a predetermined amount, the spring 87 will push the piston 86 to the left to establish communication between the pipe 97 and the chamber 72 through the port 76. The pin 83 on the piston 86 then abuts against the cap screw 84. The flow of the compressed air through the port 76 into the chamber 72 will push the piston 71 towards the right thereby applying the friction clutch as above described and consequently the air compressor is re-started. It should be noted that the lowest predetermined pressure in the pressure tank 38 should be high enough to assure sufficient power to apply the friction clutch to effect starting of the compressor.

40 When a predetermined maximum pressure in the pressure tank 38 has been reached any excess pressure will move the piston 86 to the right by overcoming the compression spring 87, since the

left-hand side of the piston 81 in the cylinder 82 is in communication through the passageway 85 with the pipe 97. It will thus be seen that when the desired maximum pressure in the pressure tank 38 has been reached, the piston 81 will move toward the right as viewed in Fig. 5 and the port 76 will be closed. The pressure of the air confined in the chamber 72 will then diminish by leakage past the piston 71 which fits loosely in the cylinder 70. Consequently the pressure between the disks 49 and 50 of the friction clutch will be lessened to allow the discs to slip and the compressor shaft 17 to stop, preventing any further operation of the air compressor.

15 By permitting the valve 95 to remain open, the operation of the air compressor including its starting and stopping will be entirely automatic so long as the electric motor 16 is operating.

Whenever the air pressure in the tank 38 falls 20 so low that the friction clutch 49, 50 cannot be applied with sufficient pressure, starting operations may be effected manually by means of the lever 89 which is pivoted at 90 and is provided with a pressure arm 91 in position to engage a cross-piece 92 of the operating lever 60. By starting 25 the motor 13 and manually applying the friction clutch 49, 50, the air compressor 16 may be operated to supply pressure to the tank 38 while the valve lever 44 occupies its horizontal position 30 shown in Fig. 2 with the passageways of the valve 43 in the positions shown in Fig. 2a. After sufficient pressure has been built up in the tank 38, the valve 81 will be automatically operated, as above explained. It should be understood that 35 the air compressor 16 is connected to the tank 38 through pipes 80, 37, and controlled by valve 43. The pressure in the tank 38 may be predetermined by the setting of the relief valve 96 in accordance with the reading on the pressure gauge 42 as 40 shown in Fig. 2.

On the truck frame 6 between the air compressor 16 and the pressure tank 38 is mounted a large car body hopper 98 for containing the granular material such as stone dust or sand which 45 is to serve as the tamping material. At the bottom of the hopper 98 is an auxiliary circular chamber 99 formed by the hollow dome-shaped housing forming the partition 100 which has a circular opening 101 in its upper side to receive 50 the valve 102. The bottom of the chamber 99 is the upper flat horizontal surface 103 of the upper side of the circular plate 104 which is secured rigidly to the dome-shaped housing 100.

The dome-shaped housing forming the partition 100 is provided with an annular flange 105 which is secured by means of cap screws 106 to the hopper floor plate 107 which is secured rigidly to the lateral longitudinal walls of the hopper 98. It will thus be seen that no communication is 55 established between the hopper 98 and the auxiliary chamber 99 except through an opening 101 in the upper side of the dome 100 and this opening is controlled by the valve 102. A vertical rod 108 is rigidly connected at its lower end to the valve 102 and the upper end of the rod 108 is pivotally connected at 109 to the lever 110 shown in Figs. 1 and 3. The lever 110 is fixed at 111 to the rock-shaft 112 which is journaled at its ends in the opposite side walls of the hopper 98. One end of 60 the rockshaft 112 is provided with an actuating lever 113 as shown in Figs. 1 and 2.

The lever arm 110 extends under the upper cross-piece 114 which is connected between the upper edges of the opposite side walls of the hopper 98. This cross-piece 114 serves as an abut-

ment to prevent opening of the valve 112 by movement upwardly from the dome 100. By depressing the lever 113, the valve 102 may be opened by downward movement to its position illustrated in dotted lines at 102' in Fig. 3. The tamping material may then flow from the hopper 98 into the auxiliary chamber 99 to fill the latter.

To facilitate the flow of the tamping material from the hopper 98 into the auxiliary chamber 99, a pipe 115 connects the pressure supply pipe 37 to the circular perforated pipe 116. By referring to Fig. 3, it will be seen that the perforations 117 in the circular pipe 116 are directed upwardly and angularly toward the valve opening 101 in the top of the housing 100. When the valve 102 is depressed to establish communication between the hopper 98 and the auxiliary chamber 99, the valve 118 may be opened by the lever 119, as shown in Figs. 1 and 2. The air under pressure will then flow from the tank 38 through the perforations 117 to aerate the tamping material, evaporate excessive moisture therefrom so as to loosen the granules and mix them to facilitate their flow through the opening 101 into the chamber 99.

After the chamber 99 has been filled with the granular tamping material, the valve 102 is again closed by lifting the lever 113 back to its initial position. The valve 102 preferably comprises an annular flexible element 120 of leather, rubber, or other flexible material which is held against a conical annular seat in the cone-shaped support 121 by means of the circular plate 122 and the lower screw-threaded end 123 at the bottom of rod 108.

The granular material that flows into the chamber 99 is forced by air pressure through the pipe 124 and the nozzle 125 for flow into the drill holes. The branch pipe 126 is connected between the air pressure supply pipe 37 and the annular chamber 127 which surrounds the depending annular skirt 128 as shown in Fig. 3. The lower edge of the annular skirt 128 is spaced above the horizontal surface 103 of the bottom plate 104. The housing 100, the skirt 128 and the peripheral support 129 together with the annular flange 105 45 may be in one integral casting and the support 129 is so shaped as to make an air-tight fit with the bottom plate 104.

The flow of the compressed air from the pipe 37 through the pipe 126 into the annular chamber 127 may be controlled by the valve 130 which is actuated by the lever 131. A pipe 132 leads from the interior of the chamber 99 into the flexible hose 124.

It will thus be seen that by affording the relatively small auxiliary chamber 99 and closing the same by means of the valve 102 after the granular tamping material has filled this chamber a predetermined pressure may be relied on to afford a uniform tamping of the granular material in the various drill holes into which it is directed by the opening of the valve 130 while the nozzle 125 is inserted into the drill holes. When the valve 130 is open compressed air has free flow around the annular air space 127 and thence 60 radially under the circular edge of the annular skirt 128. It should be understood that by reason of the angle of repose of the granular material in the chamber 99, such granular material will not fill the annular space 127. The annular distribution of the compressed air radially and inwardly under the edge of the skirt 128 will effect sufficient aeration of the granular material to produce a mixture of air and granular material to effect 65 free flow of the latter outwardly from the chamber 70 75

ber 99 through the pipes 132 and flexible hose 124 and thence through the nozzle 125. The nozzle 125 may always be open because as soon as the valve 130 is closed, the flow through the hose 124 will discontinue although still filled with the mixture of air and granular material. The auxiliary chamber 99 may be of sufficient capacity to afford operations to tamp a plurality of drill holes before it is necessary to re-open the valve 102 to 10 re-fill the chamber 99.

The diameter of the nozzle 125 should be relatively smaller than the diameter of the drill hole so as to fit loosely in the latter and provide for escape of air from the drill hole during the tamping operation. Due to the expansion of the air while traveling through the hose and the nozzle, the tamping material receives its acceleration and final velocity when emerging from the nozzle.

The greater the final velocity of the tamping material, the more effective will be the tamping action. Therefore, sufficient clearance between the outer surface of the nozzle and the drill hole should be allowed to permit free escape of the air while the tamping material is lodged at the inner 25 end of the drill hole.

As above explained, this tamping operation may be regulated by having the pressure in the tank uniform and confining the granular material in the chamber 99 by the closure of the valve 102. 30 When the air pressure is exerted in the chamber 99 the flexible element 120 tends to expand radially to hold the opening 101 tightly closed. Therefore the only escape for the compressed air in the chamber 99 will be through the pipe 132. 35 After holes have been drilled in a coal face, the cuttings may be cleaned out by means of the nozzle 133 connected to the outer end of a flexible hose 134 which communicates with the compressed air supply pipe 37. The flow of the compressed air from the pipe 37 through the nozzle 133 may be controlled by the valve 137 actuated by the lever 137'. After the drill holes have been cleaned and the blasting charges inserted, the spaces in front of the blasting charges may be 40 filled as above explained with the granular material and uniform tamping thereof secured so as to more effectively predetermine the action of the blasting down of the coal to secure the maximum amount of lump coal and a minimum 45 amount of slack, in accordance with the hardness of the coal and the amount of blasting material used in the particular system of arrangement of drill holes being employed.

During transportation of the machine shown in 50 Figs. 1 and 2 to and from the places where the blasting operations are to be carried on, the flexible sections 134 and 124 of the hose for the nozzles 125 and 133 may be supported on the horizontal plate 135 at the forward end of the machine, while the operator may stand on the supporting platform 136 at the rear end of the machine in position to control the clutch 19 while

the reel 26 is being rotated to permit paying out of the electric cable 27 which is connected to a distant source of electric supply for the electric motor 13. The operator while standing on the platform 136 may also operate the controller for the electric motor 13 and the brake lever 9. When the machine reaches the place in the mine where blasting operations are to be carried on, the forward extension of the truck frame beyond the forward axle 32 will permit the forward end of the machine to be located as close to the working face of the coal vein as the mine track 8 will permit and therefore relatively short lengths of flexible hose 124, 134 for the nozzles 125 and 133 will be sufficient.

Certain features of the apparatus herein disclosed and particularly the hopper 98 and the auxiliary chamber 99 illustrated in detail in Fig. 3 are disclosed and claimed in the application of Nils D. Levin and Ernst F. Muller, Serial No. 618,098, filed June 20, 1932.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. In a truck mounted tamping apparatus, the combination with a truck adapted to travel on a mine track, of an air compressor on said truck comprising a shaft, a motor for driving said compressor and said truck, a clutch adjacent one end of said shaft for connecting said motor thereto, and a clutch adjacent the other end of said shaft for connecting said shaft to a wheel of the truck.

2. In a truck mounted tamping apparatus, the combination with a truck adapted to travel on a mine track, of an air compressor on said truck comprising a shaft, a motor for driving said compressor and said truck, a fluid storage tank connected to said compressor, a clutch adjacent one end of said shaft for connecting said motor thereto responsive to the pressure of said tank, and a clutch adjacent the other end of said shaft for connecting said shaft to a wheel of said truck.

3. In a truck mounted tamping apparatus, the combination with a truck adapted to travel on a mine track, of an air compressor on said truck comprising a shaft, a motor for driving said compressor and said truck, a compressed air storage tank connected to said compressor, a clutch for connecting said motor to said shaft, a clutch for connecting said shaft to a wheel of said truck, said first mentioned clutch being actuated by air in said storage tank and being engaged and disengaged responsive to pressure changes therein.

ERNST F. MULLER.
